FIG. 1

FIG. 2

FIG. 3

FIGURE 1 is a top plan view of a finger ring showing my new design;

FIGURE 2 is a side elevation thereof as seen from the right of FIGURE 1; and,

FIGURE 3 is a view similar to FIGURE 1 with one of the tubes and its contents in an open position, it being understood that the other tubes may be similarly opened.

The rear surface of the finger ring band is plain and unornamented and is the same width as the front surface.

I claim:

The ornamental design for a finger ring, as shown.
